Primary Examiner — Sandra Snapp*Assistant Examiner* — Molly Loch(74) *Attorney, Agent, or Firm* — Bochner PLLC; Thomas Stanton(57) **CLAIM**

The ornamental design for a timer with flare fittings and tactile dial, as shown and described.

DESCRIPTION

FIG. 1 is a front perspective view of the design for a timer with flare fittings and tactile dial.

FIG. 2 is a top plan view thereof.

FIG. 3 is a bottom plan view thereof.

FIG. 4 is a rear elevation view thereof.

FIG. 5 is a front elevation view thereof.

FIG. 6 is a right side elevation view thereof; and,

FIG. 7 is a left side elevation view thereof.

The broken lines in the drawings show portions of the timer with flare fittings and tactile dial that form no part of the claimed design.

1 Claim, 4 Drawing Sheets(56)
